CENTER FEELER STOP MOTION

John J. Stanley, Packanack Lake, N. J., assignor,
by mesne assignments, to Steel and Alloy Tank
Company, Newark, N. J., a corporation of New
Jersey

Application March 23, 1950, Serial No. 151,418

21 Claims. (Cl. 139—376)

1

The present invention relates to filling stop motions for looms and especially filling stop motions of the center-fork type.

Filling stop motions are applied to looms, so that the loom will be stopped if the filling should break as it is inserted in the shed by the shuttle or if it should be missing for any other reason.

Filling stop motions are divided into two groups, namely, the side-fork type and the center-fork type. A single filling fork placed at one side of the loom can detect the presence or absence of only every alternate pick of filling. This is true because the filling fork can operate only when the filling extends from the cloth to the box on the same side of the loom as the fork, which occurs only when the shuttle rests in the box on that side of the loom. Naturally, the filling may break when the shuttle is traveling toward either side of the loom. With a single side-fork filling stop motion, therefore, there may be delays in the detection of a missing pick, producing thereby defective cloth.

Filling stop motions are sometimes employed which utilize a fork on each side of the loom. While these motions operate at each pick their construction is such that the loom is not stopped until the missing or broken filling has been beaten into the fell of the cloth. On certain materials objectional marks result from this beat-up action which remain in the cloth.

In an effort to produce cloth free from missing filling picks and double beat-up marks, center-fork filling motions are employed. The chief aims of this type of stop motion are to detect the absence of filling and to stop the loom before the lay reaches front center position, in the parlance of the art "to stop the loom on the pick."

Center-filling forks are mounted for engagement with the filling placed in the shed and must press this filling lightly enough so as to be held in inactive position by the filling without injuring it and at the same time must have enough force to operate the knock-off mechanism by which the loom is shut down when the absence of a filling is detected. If a switch is employed in connection with the filling stop motion, this is controlled by a transmission from the filling fork. Such a filling stop motion is not as sensitive and as quick-acting as is desirable, especially for high speed loom operations.

One object of the present invention is to provide a new and improved center-filling stop motion which is sensitive and quick-acting.

As a feature of the present invention, there is provided a center feeler fork operable to sense

the presence of the filling, a switch controlling an electric device by which the knock-off may be effected, a light simple trip operated from the fork according to filling conditions, and a transmission from a positive drive to said switch which is established or interrupted in accordance with the position of said trip. There is, therefore, no direct transmission between the fork and the switch. This permits a light mount for said fork and, therefore, sensitive and quick-acting operations.

All picks are laid in the shed while the lay is moving through the back center interval. The loom is always started with the lay in back center position to bring it up to speed before obtaining a first effective pick. Therefore, while the lay is moving from the initial back center position to front center position, there is no filling and the detection of this absence by the filling stop motion would knock off the loom prematurely. To avoid this condition, there is provided in accordance with a feature of the present invention, a device for automatically locking-out or rendering the filling stop motion inoperative during the first lay cycle after start-up.

Various other objects, features and advantages of the invention will be apparent from the following particular description and from an inspection of the accompanying drawings, in which:

Fig. 1 is a plan view of a loom with a center-fork filling stop motion and associated lock-out device embodying the present invention;

Fig. 2 is a section of the loom taken on lines 2—2 of Fig. 1;

Fig. 3 is a section of the loom taken on lines 3—3 of Fig. 1;

Fig. 4 is an enlargement of a detail portion of the transmission to the filling stop motion switch shown in Fig. 3;

Fig. 5 is a section of the filling stop motion taken on lines 5—5 of Fig. 2 and showing in full lines the motion at the back center position of the lay and in dot and dash lines the motion in the presence of a filling in the shed and after the lay has traveled a short distance from back center position towards front center position;

Fig. 6 is a section of the filling stop motion taken on lines 6—6 of Fig. 2 and corresponding to the position of the lay and the filling conditions shown in Fig. 5;

Fig. 7 is a section of the filling stop motion taken on lines 5—5 of Fig. 2, but showing the motion at the front center position of the lay during beat-up and in the presence of a filling;

Fig. 8 is a section of the filling stop motion

taken approximately along the lines 8-8 of Fig. 7, and shown with parts of the lay broken away to reveal said motion;

Fig. 9 is a section of the filling stop motion taken on lines 6-6 of Fig. 2, but showing the motion in the front center position of the lay during beat-up and in the presence of a filling;

Fig. 10 is a section of the filling stop motion taken on lines 6-6 of Fig. 2, but showing the motion after the lay has travelled a short distance from back center position towards front center position and in the absence of a filling in the shed;

Fig. 11 is a section of the filling stop motion taken on lines 6-6 of Fig. 2, but showing the stopped position of the lay somewhat before the beat-up point in the absence of filling;

Fig. 12 is a section of the lock-out device for the filling stop motion taken on lines 12-12 of Fig. 1 and shown at the instant of starting the loom, while the lay is in back center position and while the shipper handle is in loom shut-down position; and

Fig. 13 is a section of the lock-out device similar to that shown in Fig. 12, but at a later phase after the lay has reached front center position and the lock-out device has been rendered inactive.

Referring to the drawings, the filling stop motion of the present invention is shown applied to a loom having a lay 10 with its rear side secured to a pair of swords 11 each located between the frame plates 12 of the corresponding loom-side 13. The lay swords are fastened to respective rocker-shafts 14 for oscillatory operations about the axis of said rocker-shafts and are operated by the usual crank connections (not shown) to move the lay 10 back and forth along the loom.

The lay 10 comprises a beam 15 to the top of which is fastened a race plate 16 by means of a support 17. The shuttle (not shown) runs over the race plate in being thrown from one box to the other. A reed 19 on the lay 10 guides the shuttle while passing from one box to the other and serves to effect beat-up operations.

The filling stop motion of the present invention is of the center-fork type having a fork 18 adapted to operate in a lay cutout 20 located in the race plate 16 and in its support 17 near the middle of the lay 10. The fork 18 comprises a series of parallel feeler wires 21 secured to a hub 22 in the form of a sleeve, mounted on a fixed bearing rod 23 for oscillatory movement thereabout. A bracket 24 (Figs. 1 and 2) affixed to the front side of the lay beam 15 by screws 25 mounts the bearing rod 23 in fixed position by a set-screw 26.

For securing the feeler fork wires 21 to the hub 22, the top section of said hub has a series of parallel slots 27 (Figs. 2 and 8) receiving the respective ends of said wires. Screws 28 threaded into the hub 22 between these slots have their heads clamped against the ends of the feeler wires 21 to retain said wires in position and to permit their adjustment or replacement.

The feeler fork 18 is yieldably urged against the filling A in the shed B and towards the lay cutout 20 by a coil spring 30 (Figs. 1 and 2) embracing the bearing rod 23 and having one end secured to one end of the fork hub 22 and its other end secured to a collar 31. The collar 31 is affixed to the bearing rod 23 by a set-screw 32 and is adjustable thereabout to regulate the spring force with which the feeler fork 18 senses the filling in the shed.

All picks of filling are laid in the shed while the lay 10 is moving substantially about the back center position. As the lay moves toward back center, the feeler fork 18 is raised to permit passage to the filling depositing shuttle and to so position said fork that it fall will result in the blades 21 resting on the filling A. To effect the periodic raising of the feeler fork 18, there is provided a rock-shaft 35 extending along the front side of the lay 10 and having one end journaled in the bracket 24 and having its other end journaled in a bearing bracket 36 (Figs. 1 and 2) affixed to the lay beam 15 by screws 37.

The rock-shaft 35 is oscillated indirectly from the drive of the loom and directly from the lay 10 through a positive transmission comprising a long substantially upright arm or rod 40 (Figs. 1, 2 and 3) located between the frame plates 12 of the right loomside 13 and adjustably secured at its lower end by threading to a hub 41. The hub 41 embraces with a rotative fit a bearing rod 42 extending between and affixed to the right frame loomside plates 12 and is held against displacement along said bearing rod by flanking collars 43 on said latter rod. The upper end of the rod 40 is pivotally connected to one end of a short crank arm 44, the other end of which is affixed to the rock-shaft 35.

The motion of the lay 10 as it is oscillated back and forth is positively transmitted through the members 40 and 44 to the rock-shaft 35 to cause it to oscillate through a small arc. As the lay 10 moves forward (towards the left in Fig. 3), the rock-shaft 35 is rotated clockwise (Fig. 3) and as the lay moves towards the back, the rock-shaft 35 is rotated counterclockwise. The counterclockwise rotation of the rock-shaft 35 is positively transmitted to the feeler fork 18 to raise it into the raised position shown in full lines in Fig. 5 by means of a dog or arm 45 having a hub 46 (Figs. 2 and 5) at one end embracing said rock-shaft with a rotative fit and engaging at its other end an arcuate tongue extension 47 at one end of the fork hub 22. The dog hub 46 is yieldably urged clockwise (Fig. 5) about the rock-shaft 35 by means of a coil spring 48 (Fig. 2) embracing said hub and having one end secured to said hub and the other end anchored to the lay 10. A collar 50 affixed to the rock-shaft 35 by a set-screw 51 has a one-directional clutch face 52 at one end and the adjacent end of the dog hub 46 has a complementary clutch face 53 adapted to be positively engaged by the clutch face 52 on said collar when said rock-shaft is rotated counterclockwise (Fig. 5) during backward movement of the lay 10, to cause the corresponding rotation of said dog hub against the action of the spring 48 and the movement of the dog in a direction to rotate the feeler fork hub 22 counterclockwise (Fig. 5). This raises the feeler fork 18 into the position shown in full lines in Fig. 5.

During the movement of the lay 10 towards front center position, the rock-shaft 35 is rotated by this movement of the lay clockwise (Fig. 5), causing thereby the dog hub 46 under the action of the coil spring 48 to follow the collar 50 in its rotation with said rock-shaft. This releases the fork hub 22 for rotation clockwise (Fig. 5) about the bearing rod 23 under the action of the coil spring 30 and causes the feeler fork 18 to drop into sensing position on to the filling or pick A which has been laid in the shed B, as shown in dot and dash lines in Fig. 5.

75 The filling A in the shed B holds the feeler fork

18 in partially raised position, shown in dot and dash lines in Fig. 5, until the initial phase of the forward movement of the lay 10 is completed. If during this initial phase of the forward movement of the lay 10, the filling in the shed should be absent, the feeler fork 18 will drop completely and effect shut-down of the loom. The shutdown of the loom is effected under these conditions by means of a knock-off mechanism 54 (Figs. 1 and 3) which may be of any suitable construction or which may be similar to that shown in Patent No. 2,522,834 granted September 19, 1950. The knock-off mechanism shown partially in Figs. 1 and 3 is located between the frame plates 12 of the left loomside 13 and comprises a knock-off shaft 55 to which is splined a dog 56 movable therealong by means of a solenoid 59 controlled by a switch 57 forming part of the filling stop motion, as will be more fully described hereinafter. The switch 57 is preferably of the normally open snap action type. Secured at 58 to the lay sword 11 on the left loomside is a catch member 60. During normal operations, the solenoid 59 is deenergized and the dog 56 is in axial position on the shaft 55 out of the path of reciprocating movement of the catch member 60.

Upon the detection of the absence of a filling in the shed by the feeler fork 18, the switch 57 will be closed, in a manner to be described hereinafter, to cause the solenoid 59 to be energized and the dog 56 to be moved thereby along the shaft 55 into the path of the catch member 60. During this forward stroke the catch member 60 engages the dog 56 and rotates it clockwise (Fig. 3), causing thereby the shaft 55 to rotate in the corresponding direction. The shaft 55 is externally linked (not shown) to a shipper handle and shifts the said shipper handle to the "off" position and simultaneously applies the brake to shut down the loom before the lay reaches front center.

The switch 57 is supported on a bracket 65 secured to the underside of the lay beam 15 and comprises a spring-pressed plunger 66 projecting outwardly from a contact housing 67 secured to said bracket by bolts 68. When the plunger 66 is pressed inwardly into the housing 67 by the fork feeler detection of the absence of a filling in the shed, the switch in the energizing circuit of the solenoid 59 is closed to cause shut-down of the loom in the manner described. The operation of the switch plunger 66, although controlled by the operation of the feeler fork 18, is effected from a transmission coming not from the said feeler fork 18, but from the rock-shaft 35. To that end, there is provided a pawl 69 adjustably secured to the rock-shaft 35 as by a set-screw and having a peripheral notch 71 defining a catch shoulder 72. A lever 73 is pivotally secured to the switch plunger 66 at 74 and has a bevelled end adapted to be moved in and out of the pawl notch 71. The lever 73 is urged out of the pawl notch 71, and for that purpose, there is provided a U-shaped bar 75 having its bend or heel passing with a loose fit through a hole 76 in the lever 73 and having its legs 77 passing with a slide fit through the bracket 65. A coil spring 80 encircling each of the legs 77 of the U-bar 75, bears at its ends against the adjacent face of the lever 73 and against the bracket 65, to urge said lever clockwise (Fig. 6) about its pivotal connection with the switch plunger 66 at 74. The forward edge 81 of the lay beam 15 in the region of the lever 73 is bevelled to permit said lever under the action of

the coil springs 80 to be raised clear of the pawl 69, as shown in Fig. 6.

To lower the lever 73 into the path of rotation of the catch 72 on the pawl 69, upon detection of the absence of a filler in the shed by the feeler fork 18, there is provided a simple light trip 85 in the form of an upright plate guided for up and down movement across the front edge of the lay beam 15 by a guide plate 86 secured to the top of said lay beam, as for example, by screws 87 and having a slot through which said trip passes with a free slide fit. The upper end of said trip is bent to form a flange 88 which extends into a cutout 90 formed in the fork hub 22 and which engages one edge 91 of the arcuate section 92 of said hub defined by said cutout. When the fork hub 22 rotates clockwise (Fig. 10) as a result of the detection of the absence of a filling in the shed, the trip 85 is lowered by the arcuate section 92 of said hub.

The trip 85 has a long narrow defile or slot 94 to permit said trip to straddle the outer end of the lever 73 and to move said lever counterclockwise (Fig. 10) about its pivot support at 74 into the notch 71 on the pawl 69, when the absence of a filling in the shed has been detected. With the lever 73 so positioned, the continued rotation of the pawl 69 clockwise causes the catch shoulder 72 on said pawl engaging the outer end of said lever to move said lever endwise and thereby to move the plunger 66 of the switch 57 inwardly into position to close the switch contacts. This, through the operation of the knock-off mechanism, will shift the shipper handle into "off" position and will apply the brake as described, thereby shutting down the loom.

Although the operation of the filling stop motion so far described has been made apparent, it is herein summarized.

As the lay 10 is moved back and forth, the rock-shaft 35 is rocked back and forth. While the lay 10 is moving through the back center interval, the pick of filling A is being laid in the shed B. At the same time, the rock-shaft 35 is being rotated counterclockwise (Fig. 5) by the members 40 and 44, and this causes the dog 45 through the clutch engagement between its hub 46 and the collar 50 on said rock-shaft to rotate the fork hub 22 counterclockwise, and raise thereby the feeler fork 18 into the position shown in full lines in Figs. 5 and 6.

As the lay 10 moves towards front center position from the position shown in Figs. 5 and 6, the rock-shaft 35 reverses its rotation clockwise and releases thereby the fork hub 22 for rotation clockwise under the action of the spring 30, until the feeler wires 21 rest in partially raised position on the filling A in the shed B, as shown in dot and dash lines in Figs. 5 and 6. The feeler wires 21 held in this partially raised position by the filling A in the shed B during initial phase of the movement of the lay 10 towards front center position, hold the fork hub 22 against further clockwise rotation. In this held position of the fork hub 22, the lever 73 is in raised position clear of the path of rotation of the catch shoulder 72 on the pawl 69. These feeler wires 21 are held by the filling A in the shed B in partially raised position long enough to cause the catch shoulder 72 on the pawl 69 to rotate past the outer end of the lever 73 as shown in Figs. 7 and 9.

As the lay 10 continues its movement towards front center position, the feeler wires 21 ride past the filling A in the shed B and are released for

movement into the lay cutout 20. This lowers the trip 85, but only far enough to lower the lever 73 on to the periphery of the pawl 69 past or clear of the catch shoulder 72, until the lay 10 reaches the front center position shown in Figs. 7 and 9. In this position, the feeler wires 21 are held in the lay cutout 20 horizontally by the engagement of the lever 73 with the periphery of the pawl 69. During these operations, the lever 73 remains inactive and the switch 57 10 thereby remains open.

During return movement of the lay 10 towards back center position shown in Figs. 5 and 6, the rock-shaft 35 rotates counterclockwise and this raises the feeler wires 21 into open or raised position shown in full lines in Figs. 5 and 6.

If during the next forward movement of the lay 10, the filling should be absent from the shed, the feeler wires 21 instead of being held in partially raised position by the filling, drop into the lay cutout 20 during the initial phase of this movement, before the catch shoulder 72 on the pawl 69 has had a chance to rotate past the lever 73, as shown in Fig. 10. This lowers the trip 85 and causes the lever 73 to be rotated counterclockwise about the pivot axis at 74 and its outer end to be dropped into the notch 71 on the pawl 69. As the pawl 69 continues its clockwise rotation, the catch shoulder 72 on the pawl 69 engaging the outer end of the lever 73 pushes this lever endwise against the action of the springs 80 and closes thereby the switch 57, by the time the lay 10 reaches the front center position shown in Fig. 11. This energizes the solenoid 59 of the knock-off mechanism and shuts down the loom, in the manner described.

All filling picks are laid in the shed while the lay 10 moves through the back center interval backwards. The loom is started with the lay 10 in back center position to bring it up to speed before obtaining a first effective pick. Therefore, while the lay 10 is moving from the initial back center position to front center position, there is no filling in the shed and the detection of this absence by the filling stop motion would knock off the loom prematurely. To avoid this, there is provided a lock-out device shown in Figs. 1, 12 and 13 and comprising a switch 100, preferably of the normally open snap action type, mounted on the inner side of the outer frame plate 12 of the left loomside 13 by bolts 101 and spacers 102 and held between two smaller frame plates 103 supported by said bolts. The switch 100 is connected in series with the switch 57 in the circuit of the solenoid 59 through leads 105 connected to an outlet box 106 secured to the inner side of the outer frame plate 12 of the right loomside 13. The lock-out switch 100 has a spring-pressed plunger 107 which is controlled through a shipper handle 108 secured to a shipper shaft 110 and which is operated by a substantially horizontal trip bolt 111 between the frame plates 103. The trip bolt 111 has a connection with the shipper shaft 110 comprising a crank arm 112 secured to said shipper shaft and having its outer end pivotally connected to one end of a link 113, the other end being pivotally secured to a latch 114 connected to the trip bolt 111. The latch 114 is in the form of a flat plate having a lower tongue 115 extending into a slot 116 in the trip bolt 111 and pivotally connected thereto by a pin 117. A shoulder 118 on this latch is seated on the upper edge of the trip bolt 111, when said trip bolt is in inoperative position shown in full lines in Fig. 12.

The trip bolt 111 is supported for substantially endwise movement by means of a parallel motion link mechanism comprising a pair of parallel inclined links 120 pivotally connected at 121 to said bolt and pivotally connected at 122 by pins extending between and secured to the frame plates 103. An inclined spring 123 parallel to the links 120 has one end secured to the trip bolt 111 through a short link 124 pivotally mounted in the pin 117 and has its other end anchored to a pin 125 extending between and secured to the frame plate 103. The inclined links 120 supporting the trip bolt 111 and the inclined spring 123 are arranged to hold the trip bolt 111 in either one of its two extreme positions shown in Figs. 12 and 13 and to snap said trip bolt into the other extreme position under the action of said spring once said links and said spring move past vertical position or dead center.

For moving the trip bolt 111 into switch closing position through the operation of the lay 10, with minimum of impact and shock, there is provided a tappet rod 130 having a slide fit in an upward end offset 131 in the trip bolt 111 and yieldably pressed outwardly by means of a coil spring 132.

In Fig. 12, the shipper handle 108 is shown in "off" or loom shut-down position C, the lay 10 is shown in back center position, the trip bolt 111 is in rearward position and the switch 100 is open. The circuit of the solenoid 59 of the knock-off mechanism, therefore, remains open regardless of the position of the switch 57 of the filling stop motion.

When the shipper handle 108 is shifted to the "on" position D, the shipper shaft 110 is rotated clockwise (Fig. 12) and this causes the connection 112, 113 and 114 between said shaft and the trip bolt 111 to assume the position shown in dot and dash lines in Fig. 12 without disturbing said trip bolt.

The shifting of the shipper handle 108 into the "on" position D, starts the movement of the lay 10 forwardly from the back center position shown. During this initial forward movement of the lay 10, the absence of a filling in the shed does not energize the solenoid 59 of the knock-off mechanism and does not shut down the loom, since this mechanism is locked-out by the open switch 100.

As soon as the lay 10 reaches position near front center, the front side of said lay engages the spring-pressed tappet rod 130 and moves thereby the trip bolt 111 forwardly endwise. This trip bolt snaps into position to engage the plunger 107 and to close thereby the switch 100, as shown in Fig. 13, as soon as the links 120 and spring 123 move past vertical or dead center position, and is held in this position by said spring, until it is moved back by the rotation of the shipper shaft 110 into loom shut-down position shown in Fig. 12. In the inoperative position of the lock-out device shown in Fig. 13, the forwardly shifted position of the trip bolt 111 causes the shoulder 118 on the latch 114 to seat on the upper edge of the trip bolt 111. In this position of the trip bolt 111, a slight clearance 135 is afforded between the forward side of the lay 10 in front center position and the head of the tappet rod 130, so that this tappet rod is not engaged by the lay 10 during its normal operations.

With the switch 100 closed, the loom is placed under control of the filling stop motion in the manner described.

When the shipper shaft 110 is rotated into loom shut-down position by manipulation of the shipper handle 108 or by operation of the knock-off mechanism, the counterclockwise rotation of said shipper shaft 110 will cause the trip bolt 111 to be shifted rearwardly into position shown in Fig. 12, to release the switch 100 for spring opening action. The trip bolt 111 is so shifted by the connection 112, 113 and 114 from the shipper shaft 110, because of the seating engagement of the shoulder 118 on the latch 114 with the upper edge of said trip bolt.

While the invention has been described with particular reference to a specific embodiment, it is to be understood that it is not to be limited thereto, but is to be construed broadly and restricted solely by the appended claims.

What is claimed is:

1. In a loom having a lay, a motion for reciprocating said lay, and a loom knock-off mechanism, a filling stop motion comprising a feeler and actuating means therefor for sensing the presence or absence of a filling, a member for controlling the operation of said knock-off mechanism, a transmission between said lay motion and said controlling member for operating said controlling member into loom knock-off position, and means for establishing or interrupting said transmission in accordance with the sensing operation of said feeler.

2. In a filling stop motion for a loom, a feeler and actuating means therefor for sensing the presence or absence of a filling, a switch for controlling the operation of a loom knock-off, a drive independent of said feeler, a transmission from said drive to said switch to operate said switch, and means for establishing or interrupting said transmission in accordance with the sensing operation of said feeler.

3. In a filling stop motion for a loom, a feeler and actuating means therefor operable during each weaving cycle for sensing the presence or absence of a filling in the weaving shed, a switch for controlling the operation of a loom knock-off, a drive independent of said feeler but constituting part of the mechanism for operating the loom through successive weaving cycles, a transmission from said drive to said switch for operating said switch but normally interrupted during each cycle when said feeler senses the presence of a filling in the shed during the cycle, and means automatically operable when said feeler senses the absence of a filling in the shed during the cycle for establishing said transmission and for operating thereby said switch into loom knock-off position.

4. In a loom having a reciprocable lay, a filling stop motion comprising a feeler and actuating means therefor for sensing the presence or absence of a filling in the weaving shed, a switch for controlling the operation of a loom knock-off, a transmission between said lay and said switch to operate said switch, and means for establishing or interrupting said transmission in accordance with the sensing operation of said feeler.

5. In a filling stop motion for a loom, a feeler movable into position to sense the presence or absence of a filling in a weaving shed, feeler actuating means, a switch for controlling the operation of a loom knock-off, a drive independent of said feeler, a transmission from said drive to said switch to operate said switch and comprising a member movable into or out of motion-transmitting position, means operable as long

as said feeler senses the presence of a filling in a weaving shed during each weaving cycle for holding said transmission member out of motion-transmitting position and for maintaining thereby said transmission interrupted, and means automatically operable when said feeler senses the absence of a filling in a shed during a weaving cycle for moving said transmission member into motion-transmitting position to establish said transmission and to operate thereby said switch into loom knock-off position.

6. In a loom having a reciprocable lay, a filling stop motion of the center-fork type, comprising a center feeler fork carried by the lay for sensing the presence or absence of a filling, feeler actuating means, a member for controlling the operation of a loom knock-off, a transmission between said lay and said controlling member for operating said controlling member into loom knock-off position and comprising a member movable into or out of motion-transmitting position, means operable as long as said feeler fork senses the presence of a filling during each weaving cycle for holding said transmission member out of motion-transmitting position and for maintaining thereby said transmission interrupted, and means automatically operable when said feeler fork senses the absence of a filling during a weaving cycle for moving said transmission member into motion transmitting position to establish said transmission and to operate thereby said controlling member into loom knock-off position.

7. In a loom having a reciprocable lay, a filling stop motion comprising a feeler fork carried by said lay for sensing the presence or absence of a filling, feeler actuating means, a drive member on said lay, means for operating said drive member by the reciprocable movement of said lay, a switch on said lay for controlling the operation of a loom knock-off, a transmission between said drive member and said switch carried by said lay to operate said switch and comprising a member movable into or out of motion transmitting position, means for normally maintaining said transmission member out of motion transmitting position and for maintaining thereby said transmission interrupted, and means automatically operable when said feeler fork sense the absence of a filling during a weaving cycle for moving said transmission member into motion transmitting position to establish said transmission and to operate thereby said switch into loom knock-off position.

8. In a loom having a reciprocable lay, a filling stop motion comprising a feeler and actuating means therefor for sensing the presence or absence of a filling during each weaving cycle, a member for controlling the operation of a loom knock-off, a drive shaft, means operable by the reciprocable movement of said lay for rocking said drive shaft, a transmission between said drive shaft and said controlling member for operating said controlling member into loom knock-off position, means for normally maintaining said transmission interrupted, and means automatically operable when said feeler senses the absence of a filling during a weaving cycle for establishing said transmission to operate said controlling member into loom knock-off position.

9. In a loom, a reciprocable lay having a cutout across the top and a filling stop motion of the centerfork type, comprising a feeler fork operable in and out of said lay cutout for sensing the presence or absence of a filling dur-

ing each weaving cycle, a hub on the front of said lay supporting said feeler for angular movement into or out of filling sensing position with respect to said lay cutout, a drive shaft supported on said lay along the front thereof and below said hub, means operatable by the reciprocal movement of said lay for rocking said drive shaft, a dog mounted on said drive shaft and adapted to engage said hub when said dog is turned in one direction about the axis of said drive shaft to rotate said hub and to lift thereby said feeler fork into open position, a unidirectional clutch between said drive shaft and said dog for turning said dog in said direction during a part of each weaving cycle when said drive shaft is rotating in one direction and operatable during another part of each weaving cycle to release said hub for fork sensing operation when said drive shaft is rotating in the opposite direction, and means operatable when said feeler fork senses the absence of a filling during a weaving cycle for effecting shut-down of the loom.

10. In a loom, a reciprocal lay, and a filling stop motion comprising a feeler mounted for movement into filling sensing position and out of filling sensing position during each weaving cycle, a drive shaft, means operatable by the reciprocal movement of said lay for rotating said drive shaft, a connection between said drive shaft and said feeler for moving said feeler into open position during a period of each weaving cycle, means for releasing said connection during another period of each cycle to permit said feeler to move into filling sensing position, a switch for controlling the operation of a loom knock-off, a transmission between said drive shaft and said switch to operate said switch into loom knock-off position, said transmission being normally interrupted, and means automatically operatable when said feeler senses the absence of a filling during a weaving cycle for establishing said transmission to operate thereby said switch into loom knock-off position.

11. In a loom having a reciprocal lay, a filling stop motion comprising a feeler and actuating means therefor for sensing the presence or absence of a filling during each weaving cycle, a switch for controlling the operation of a loom knock-off, a drive shaft, means operatable in accordance with the reciprocal movement of said lay for rocking said drive shaft, a pawl fastened to said shaft for rocking movement therewith and having a catch, a motion-transmitting member between said pawl and said switch movable into and out of the path of movement of said pawl catch, means for normally maintaining said motion transmitting member out of the path of movement of said pawl catch, and means automatically operatable when said feeler senses the absence of a filling during a weaving cycle for moving said motion transmitting member into the path of movement of said pawl catch to transmit motion from said drive shaft to said switch and to operate thereby said switch into loom knock-off position.

12. In a loom having a reciprocal lay, a filling stop motion comprising a feeler and actuating means therefor for sensing the presence or absence of a filling during each weaving cycle, a hub supporting said feeler for movement into and out of filling sensing position, a switch for controlling the operation of a loom knock-off, a drive shaft, means operatable in accordance with the reciprocal movement of said lay for rocking said drive shaft, a pawl fastened to said shaft for rocking

movement therewith and having a catch, a lever between said pawl and said switch below said hub movable angularly up and out of the path of movement of said pawl catch or down into the path of movement of said pawl catch, spring means normally maintaining said lever in raised position out of the path of movement of said pawl catch, and a trip with a slot at one end straddling said lever and engaged by said feeler hub, said trip being adapted to be moved by said hub into position to depress said lever into the path of movement of said pawl catch when said feeler senses the absence of a filling during a weaving cycle and to cause thereby operation of said switch into loom knock-off position.

13. In a filling stop motion for a loom, a feeler and actuating means thereof for sensing the presence or absence of a filling, a switch for controlling the operation of a loom knock-off having a contact plunger, a drive independent of said feeler and operatable in accordance with the lay motion, and a transmission from said drive to said switch to operate said switch and comprising a pawl having a catch operated by said drive, a lever pivotally supported on said plunger and movable about its pivot support in and out of the path of movement of said catch, means normally maintaining said lever in position out of the path of movement of said pawl catch, and means for moving said lever about its pivot support into the path of movement of said pawl catch when the absence of a filling has been detected by said feeler for operating said switch into loom knock-off position.

14. In a loom, a lay movable backwards and forwards and having a cutout across its top near the center, a filling stop motion of the center-feeler type comprising a feeler fork, a hub mounted on the forward side of said lay supporting said feeler fork for angular movement towards and away from said cutout, spring means urging said hub in position to urge said feeler fork towards said lay cutout, into filling sensing position, a shaft mounted on the forward side of said lay below said hub, means operated by the movement of the lay for rocking said shaft in one direction during the backward movement of the lay and in the opposite direction during the forward movement of the lay, a connection between said shaft and said hub for positively raising said feeler fork into open position away from said cutout and against the action of said spring means, while said lay is moving backwards, said connection being automatically releasable during the forward movement of the lay to permit said feeler fork to drop under the action of said spring means, onto the filling laid in the shed, a switch for controlling the operation of a loom knock-off connected to the lower side of said lay and having a contact plunger, a pawl secured to said shaft for rocking movement therewith and having a catch, a lever pivotally secured to said plunger and movable about its pivot support in and out of the path of movement of said catch during forward movement of said lay, spring means urging said lever out of the path of movement of said catch, and a trip between said hub and said lever operated during forward movement of said lay by said hub into position to move the lever in the path of movement of said catch and against the action of said last mentioned spring means, when said feeler fork drops far enough into said lay cutout as the result of the absence of a filling in the shed, whereby said pawl moves said lever and thereby

through said plunger moves said switch into loom knock-off position.

15. In a loom having a lay, a center filling stop motion having a switch controlling a loom knock-off and closed when the absence of a filling is sensed, and lock-out means for said stop motion comprising a second switch in series with said first switch, means maintaining said switch open when said loom is shut-down and during the first forward stroke of the lay after loom start-up, whereby said stop motion is rendered inoperative, and means for closing said switch automatically near the end of said first forward stroke of the lay, for rendering said stop motion operative thereafter.

16. In a loom having a lay, a center filling stop motion, and lock-out means for automatically rendering said stop motion inoperative during the first forward stroke of the lay after loom start-up and for automatically rendering said stop motion operative after said first forward stroke of the lay, and comprising a switch controlling the operativeness or inoperativeness of said stop motion, a movable piece between said lay and said switch in the path of movement of said lay and adapted to be engaged by said lay when it reaches near front center position, and to be moved thereby from an inactive position into an active position against said switch, whereby said switch is operated into stop motion lock-out position, and means for moving said movable piece into said inactive position automatically upon loom shut-downs, to release said switch and to thereby lock-out said stop motion.

17. In a loom, the combination as described in claim 16, comprising a shipper shaft, the means for moving said movable piece into said inactive position upon loom shut-downs comprising a connection between said shaft and said movable piece including a latch operable to move said movable piece into said inactive position when said shaft is turned into loom shut-down position, but automatically operable to permit said shaft to be turned into loom start-up position, without disturbing the inactive position of said movable piece.

18. In a loom, the combination as described in claim 16, comprising a spring-snap mounting for said movable piece, operable to move said movable piece in either one of its positions by spring-snap action after passing dead center position.

19. In a loom, the combination as described in claim 16, comprising a spring-snap mounting for said movable piece operable to move said movable piece in either one of its positions by spring-snap action after passing dead center position, said movable piece in said switch operating active position being spaced from said lay in front center position, whereby the lay in subsequent operations of the loom before the next shut-down does not engage said movable piece.

20. In a loom having a lay, a center filling stop motion, and lock-out means for automatically rendering said stop motion inoperative during the first forward stroke of the lay after loom start-up and for automatically rendering said stop motion operative after said first forward stroke of the lay and comprising a switch con-

trolling the operativeness or inoperativeness of said stop motion, a trip bolt between the lay and the switch, a spring-snap mounting for said bolt permitting said bolt to move endwise and snapping said bolt into either one of two extreme positions after passing dead center position and comprising parallel motion links and a spring, said bolt in one of said extreme positions engaging said switch and maintaining it in position to render said stop motion operative, and in its other of said extreme positions being spaced from said switch and being adapted to be engaged by said lay when it reaches near front center position and to be moved thereby into said first extreme switch-engaging position, and means for moving said trip bolt into said other extreme position automatically upon loom shut-downs to release said switch and to render thereby said stop motion inoperative.

21. In a loom having a lay and a shipper shaft, a center filling stop motion, and lock-out means for automatically rendering said stop motion inoperative during the first forward stroke of the loom after loom start-up and for automatically rendering said stop motion operative after said first forward stroke of the lay and comprising a switch controlling the operativeness or inoperativeness of said stop motion, a trip bolt between the lay and the switch, means mounting said trip bolt for endwise movement into either one of two extreme positions, said bolt in one of said extreme positions engaging said switch and maintaining it in position to render said stop motion operative, and in its other of said extreme positions being spaced from said switch and being adapted to be engaged by said lay when it reaches near front center position and to be moved thereby into said first extreme switch engaging position, and a connection between said shaft and said trip bolt including a crank arm secured to said shaft, a latch pivotally secured to said trip bolt, and a link between said latch and said crank arm pivotally secured thereto, said latch having a shoulder engaging said trip bolt when said shaft is turned into loom shut-down position to move said trip bolt into said other extreme position, said latch turning idly about its pivot connection with said trip bolt, when said shaft is turned into loom start-up position.
